No. 835,614.

PATENTED NOV. 13, 1906.

W. F. HEBRANK.

AUTOMATIC SELF HEATING CAPPING DEVICE.

APPLICATION FILED DEC. 18, 1905.

UNITED STATES PATENT OFFICE.

WILLIAM F. HEBRANK, OF GREENVILLE, ILLINOIS.

AUTOMATIC SELF-HEATING CAPPING DEVICE.

No. 835,614.

Specification of Letters Patent.

Patented Nov. 13, 1906.

Application filed December 18, 1905. Serial No. 292,394.

To all whom it may concern:

Be it known that I, WILLIAM F. HEBRANK, a citizen of the United States, residing at Greenville, in the county of Bond and State 5 of Illinois, have invented a new and useful Automatic Self-Heating Capping Device, of which the following is a specification.

This invention relates to tools for capping cans, such as those containing milk, paints, 10 mineral and other waters, &c.; and its object is to provide a tool of this character having means whereby the same is rendered self-heating.

A still further object is to provide a tool of 15 simple, durable, and inexpensive construction which presents an attractive appearance and which can be easily manipulated.

With the above and other objects in view the invention consists of a tubular handle 20 adapted to be removably connected to a suitable fuel-supply, and this handle is provided with a tubular guide in which is mounted a stem which is slidably mounted within a heating-iron of novel form, the end of the 25 stem being held normally projected beyond said iron. Means are provided whereby combustible gases may be conveyed from the handle to the interior of the iron, where they may be ignited to heat the iron and the rod 30 contained therein.

The invention also consists of certain other novel features of construction and combinations of parts, which will be hereinafter more fully described, and pointed out in the claims.

35 In the accompanying drawings is shown the preferred form of the invention.

In said drawings, Figure I is a vertical section through the tool and showing by dotted lines the position of the weight when raised. 40 Fig. II is an elevation of one part of the tool below the handle; and Fig. III is a section on the line III III, Fig. II.

Referring to the figures by characters of reference, 1 is a handle having a tube 2 extending therethrough and extending beyond the ends thereof. A joint 3 is swiveled to one end of this tube and constitutes a means for connecting a flexible tube 4 to the tool. The other end of the tube 2 is screwed into a 45 coupling 5, having a longitudinally-slotted guide-tube 6 screwed thereinto and closed at its upper end by a screw-block 7, while its other end is screwed into a tubular heating-iron 8, having an enlarged end 9, from which 50 extends a jacket 10, which surrounds the heating-iron and forms an annular compart-

ment 11 therein. Openings 12 are formed within the jacket adjacent the bottom of this compartment. A slotted washer 13 is clamped upon the inner end of the heating-iron in any desired manner, as by means of a lock-nut 14, and this nut constitutes a stop for a tubular weight 15, which is slidably mounted on the guide-tube 6 and has a longitudinally-extending slot 16 formed therein. 60

A screw-plug 17 is located within the coupling 5 and has an angular passage 18 therein, into which projects a discharge-tube 19, which extends into the compartment 11 and terminates close to the openings 12. Set-screws 20 extend into opposite portions of the weight 15 and through the slots in guide-tube 6, and these screws clamp upon a stem 21, which is slidably mounted within the guide-tube and the heating-iron and has a 70 pointed end 22, which is held normally projected beyond the heating-iron by the weight 15.

It is believed that the operation of this tool will be fully understood from the foregoing 80 description when read in connection with the drawings. Combustible gases are conducted to the tube 2 through the hose 4 and joint 3 and are discharged into the coupling 5, from which they will pass through the plug 17 to 85 the tube 19. Air enters the compartment 11 through the openings 12, and therefore the gases escaping from the tube 19 may be ignited at this point, so as to thoroughly heat the iron 8 and the stem 21, which is disposed 90 therein. By pressing the end of the stem against a can or other object said stem will be forced longitudinally into the tube 6, and the weight 15 by reason of its connection with the stem will be correspondingly moved 95 upon the tube. As soon as the tool is raised from the can said weight will return by gravity into position upon the lock-nut 14 and will again project the stem 21 beyond the iron. By means of the set-screws 20 the 100 length of the projecting portion of the stem can be regulated.

It will be seen that all parts of the tool can be readily detached and new ones replaced in the event of wear or breakage.

The tool can be very conveniently manipulated and will be found extremely efficient.

The preferred form of the invention has been set forth in the foregoing description; but I do not limit myself thereto, as I am 110 aware that modifications may be made therein without departing from the spirit or sac-

rificing the advantages thereof, and I therefore reserve the right to make such changes as fairly fall within the scope of the invention.

5 What is claimed is—

1. In a tool of the character described the combination with a tubular heating-iron having an enlarged end, and an annular compartment having air-inlet openings in the wall thereof; of a tubular handle having a fuel-inlet, a slotted tubular connection between the handle and the interior of the iron, a stem slidably mounted within the iron and tubular connection, a weight straddling and slidably mounted upon said extension and connected to the stem, and a tube for conducting fuel from the handle to the annular compartment at a point adjacent the openings therein.

2. In a tool of the character described the combination with a tubular handle having a fuel-inlet; of a tubular iron having an enlarged end and an integral jacket forming an annular compartment having apertures in the wall thereof, a longitudinally-slotted tubular connection between the handle and the iron, a tube extending from the handle and into the annular compartment for conveying fuel to said compartment, a screw-plug within the tubular connection, a weight straddling and slidably mounted upon the tubular connection, a stem slidably mounted within the iron and tubular connection, and means for connecting said stem to the weight.

WM. F. HEBRANK.
